APPARATUS FOR THE BORING OF WELLS
OR SHAFTS, AND FOR LIKE OPERATIONS

Pierre Jean Marie Theodore Allard, Ste.-Adresse, France, assignor to Societe Francaise de Construction de Bennes Automatiques, Le Havre, France, a company of France

Original application May 26, 1933, Serial No. 672,967. Divided and this application August 22, 1934, Serial No. 740,864. In France August 25, 1932

1 Claim. (Cl. 37—71)

The present invention relates to an apparatus for the boring, the excavation, the sinking of wells or shafts, and like operations, consisting of a grab the operating tools of which are mounted 5 at the bottom of an elongated main body having a practically cylindrical form and adapted to guide the said grab in the cavity to be excavated, the weight of the body being sufficient to enable its use for operating upon the soil by percussion. 10 This arrangement provides for the construction of small grabs having a relatively considerable weight, and especially employed for the sinking of wells.

Such an apparatus has been described in my 15 copending application Serial No. 672,967 filed May 26, 1933, of which the present case is a divisional application.

An object of my present invention is to provide 20 improvements in the construction of the main substantially cylindrical body of the apparatus.

In the accompanying drawing, which is given solely by way of example:

Fig. 1 is a diagrammatic vertical section of a 25 grab in conformity with the invention.

Fig. 2 is a longitudinal section of the piston provided with longitudinal channels in view of digging in submerged grounds.

Fig. 3 is a corresponding plan view.

Fig. 4 shows a longitudinal section of the upper 30 part of the grab which also is provided with channels.

Fig. 5 is a corresponding plan view.

In the form of construction represented in Fig. 1, the apparatus comprises an elongated main 35 body the external form of which is practically cylindrical, or preferably somewhat tapered. This body is provided at the top with a ring or hook 2 for attaching a cable 3. The said body contains the operating mechanism, which includes 40 a set of pulleys 6, and a second set of pulleys 8 supported by a block 10 which is slidable in the body 1.

A cable 13 is attached at one end to the body 1, and passes over the set of pulleys 6 and 8.

To the lower end of the body 1 is secured a 45 ring 17 which is coaxially mounted with respect to said body, and whose internal diameter is preferably smaller than the external diameter of the block 10.

The ring 17 carries scoops 20, mounted upon spindles 21.

A bracket 24 is secured to the lower end of the block 10, and to the horizontal arms of scoops 20.

The apparatus may be thrown down upon the 50 ground to be excavated, the grab being open. The

scoops 20 penetrate the ground and when they are closed and the grab is lifted they also gather and raise the disaggregated material.

In the form of construction according to my 5 present invention, the elongated body of the grab, the outer shape of which is practically cylindrical or preferably somewhat tapered, is formed by the superposition of a cap 1 with rounded top, a ring 1^a (which is optional), a cylindrical part 1^b, and a lower ring 17 upon which are pivoted, at 21, the 10 scoops 20 or like parts of the grab. The said scoops are connected with a piston 10 which is 15 slideable in the cylinder 1^b under the action of a cable 13 mounted on the set of pulleys 6 and 8. The lifting cable 3 is attached to the cap 1 at 2.

As the hemispherical cap 1 forming the head of 20 the grab is removable, it affords access to the interior of the grab, for instance should the piston be accidentally held fast.

When working in submerged ground, in order 25 to facilitate the descent of the grab in the water and to avoid effects of suction which would take place especially in the case where the grab operates in a tube, the piston 10 is not solid but contains spaces or channels 48 affording the greatest possible passage for the water. The arrangement shown in Figs. 2 and 3 may for instance be employed.

The cap 1 forming the rounded end of the grab 30 is pierced with apertures or channels 49 for the circulation of water, for instance according to the arrangement shown in Figs. 4 and 5.

In the case of submerged and soft ground, the 35 pivot joints 21 of the scoops are preferably situated outside of the diameter of the cylindrical parts 1^a—1^b and of the rounded cap 1, in order to avoid effects of suction when the grab is raised, as this leaves a sufficient space between the cylindrical part and the inner walls of the tube or the 40 well.

Apparatus of the type herein described are to 45 be employed for operating in the ground by percussion. They may also be used as a ram, in order to break up the ground by ramming. They may be dropped from a point having a height attaining several meters. They are closed afterwards in order to grasp the material to be removed by means of the scoops 20.

The use of such apparatus offers particular 50 advantages for the sinking of shafts or wells of reduced size which require the use of small grabs, as the practically cylindrical body 1 allows the use of the available size of the grab to the maxi- 55

mum degree, and to employ a considerable weight even for a small apparatus. The body 1 adapts itself to the diameter of the excavation, and serves as a means for guiding the grab.

5 The said apparatus have a very substantial construction. Due to the practically cylindrical form of the body 1, which replaces the usual frames or traction rods of the grabs, the said body will withstand very hard shocks.

10 As the closing mechanism is contained in the body 1, which is closed at the top and the lower part of which is stopped by the block 10, the said mechanism is protected against contact with sand, earth or stones which might offer prejudice to the 15 working of the apparatus.

15 It is evident that the devices comprising two cables for the opening and closing of the grab, might be replaced by any other known device in current use for grabs, having one or more cables 20 or chains for the opening and one or more cables or chains for the closing.

Obviously, the invention is not limited to the forms of construction herein described and represented, which are given solely by way of example.

25 Having now described my invention what I claim as new and desire to secure by Letters Patent is:

An apparatus of the kind referred to comprising a grab device, an elongated preferably cylindrical body combined with said grab, having relatively thick walls and high weight, and intended for the guiding of the grab device in the bore formed by the excavation of the earth, operating means adapted to bore the ground by violent impact thereon and to evacuate the disaggregated materials, mounted preferably in a detachable way on the bottom of said elongated body, a heavy 10 block slidably mounted within said elongated body, and forming a substantially closed chamber in the upper part of said elongated body, controlling means for causing the sliding of said block mounted and entirely concealed within said 15 chamber, and means for connecting said block with said operating means and providing for the opening and the closing of these latter means, said apparatus being intended for the working in submerged grounds and comprising preferably 20 longitudinal channel means provided in the top part of the elongated body and in the slidable block for the evacuation of water.

PIERRE JEAN MARIE

THEODORE ALLARD.
